(57) **CLAIM**

The ornamental design for a head worn cockpit avionics display, as shown and described.

DESCRIPTION

FIG. 1 is a perspective view of a head worn cockpit avionics display showing my new design, the broken lines indicate environmental structure and form no part of the claimed design;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines of the figures are depicted for illustrative purposes, and form no part of the claimed design.

The claimed "head worn cockpit avionics display" is used as a visual instrument interface for assisting in situational awareness.

1 Claim, 7 Drawing Sheets
